CANDELABRA

Frederick Russell Woodward, Attleboro, Mass., assignor
to Gorham Corporation, Providence, R.I.

Filed July 7, 1965, Ser. No. 86,061

Term of patent 14 years

(Cl. D48—2)

Fig. 1

FIG. 1 is a side elevational view of a candelabra showing my new design. It is understood that the appearance of the right arm of the candelabra which is shown in broken lines for ease of illustration, is identical to the left arm.

FIG. 2 is a top plan view seen from the direction of arrows 2-2 in FIG. 1.

FIG. 3 is a sectional view taken on line 3-3 of FIG. 1.

FIG. 4 is a sectional view taken on line 4-4 of FIG. 1.

FIG. 5 is a fragmentary view of the support arm as seen in the direction of arrows 5-5 of FIG. 1.

FIG. 6 is a sectional view taken on the line 6-6 of FIG. 1.

The ornamentation is slightly raised with respect to the surfaces of the candelabra.

The side opposite that shown in FIG. 1 is a mirror image of the side shown.

I claim:

The ornamental design for a candelabra, as shown and described.
